(57) **CLAIM**

I claim the ornamental design for a bag carrier, as shown and described.

DESCRIPTION

FIG. 1 is a perspective view of a bag carrier, showing my new design;

FIG. 2 is a front elevational view thereof, the rear elevational view being identical to this Figure;

FIG. 3 is a right end elevational view thereof, the left end elevational view being identical to this Figure;

FIG. 4 is a top plan view thereof; and,

FIG. 5 is a bottom plan view thereof.
